UNITED STATES PATENT OFFICE.

FRANK THEODORE WILLIAMS, OF MERIDEN, CONNECTICUT, ASSIGNOR TO
THE EDWARD MILLER & COMPANY, OF CONNECTICUT.

LAMP-BURNER.

SPECIFICATION forming part of Letters Patent No. 659,334, dated October 9, 1900.

Application filed July 19, 1900. Serial No. 24,180. (No model.)

To all whom it may concern:

Be it known that I, FRANK THEODORE WILLIAMS, a citizen of the United States, residing at Meriden, Connecticut, have invented certain new and useful Improvements in Lamp-Burners, of which the following is a full, clear, and exact description.

My invention relates to lamp-burners; and my object is to improve the construction of the same.

One of my principal objects is to provide a central-draft burner of the kind in which the wick burns on its outer circumference and is substantially protected at its top, with a gas-generating space within the inner circumference of the wick and at its upper portion to supply the gas so generated to the flame.

In the drawings showing the preferred embodiment of my invention, Figure 1 is a central vertical section with the parts in their raised position ready for lighting. Fig. 2 is the same view with the parts in their lowered position, and Fig. 3 is a top view of the extinguisher-flange.

25 In the above preferred embodiment 1 is the outer wick-tube, and 2 the inner wick-tube, within which a wick 3 may move. Within the inner wick-tube is located a wall 4, preferably cylindrical, as shown. I prefer to fix this wall 30 with relation to the inner tube and to hold it away from the inner tube, so that there will be a space between it and the wick. To accomplish both these results, I have provided a spacer 5, which in the embodiment shown 35 consists of an inwardly-turned flange at the top of the inner tube.

6 is in this embodiment an extinguisher formed of a thin ring of metal perforated on its inner edge, as shown in Fig. 3. This extinguisher rests on top of the wick, and in this embodiment protects the top thereof from the flame. The flame burns from the outside of the wick, and these perforations 7 are preferably located inside of the wick, so that the 45 charred particles of the wick will not clog up the perforations. The extinguisher is freely movable up and down with the wick, and I prefer to attach the same to the perforated spreader 8, which is freely movable on the 50 cylindrical wall 4.

9 is a rod fixed within the inner wick-tube and carrying a stop 10, which may be removable, if desired, to limit the upward movement of the spreader, and therefore, in this embodiment, of the wick.

When the parts are in the raised position shown in Fig. 1, the spreader 5, together with the wall 4, will form a gas-space 11 at the upper end of the wick, and in this space gas will be generated from the inner side of the wick 60 by the heat, and the gas will pass out through the perforations 7 to the flame. In this way I have provided a construction which gives a brilliant and steady flame and which is cheap and easily taken apart and reassembled.

The construction above described is broadly claimed in my former application, filed the 18th day of July, 1900, Serial No. 23,991.

I am aware that many changes may be made from the construction herein disclosed without departing from the spirit of my invention, and I therefore do not desire to be limited to the particular embodiment herein shown and described.

What I claim is—

1. In a lamp-burner in combination, an inner and an outer wick-tube, an extinguisher adapted to rest on top of a wick and be moved up above said outer tube, a stationary wall smaller than and located inside of said inner tube, a spacer to hold said wall away from said wick and form, with said wall, a gas-space at the inside of said wick, one of said parts being perforated to allow the escape of gas from said space to the flame.

2. In a lamp-burner in combination, an inner and an outer wick-tube, an extinguisher adapted to rest on top of a wick and be moved up above said outer tube, a stationary cylindrical wall smaller than and located inside of said inner tube, a spacer below said extinguisher and between said wall and inner tube to form, with said wall, a gas-space at the inside of said wick, said extinguisher being perforated to allow the escape of gas from said space to the flame.

3. In a lamp-burner in combination, an inner and an outer wick-tube, an extinguisher adapted to rest on top of a wick and be moved up above said outer tube to allow the flame

to burn at the outside of said wick, a stationary cylindrical wall smaller than and located inside of said inner tube, a spacer below said extinguisher and between said wall and inner tube to form, with said wall, a gas-space at the inside of said wick, a perforated spreader movable up and down said wall and fixed to said extinguisher, said extinguisher being

perforated to allow the escape of gas from said space to the flame.

Signed at Meriden, Connecticut, this 16th day of July, 1900.

FRANK THEODORE WILLIAMS.
